UNITED STATES PATENT OFFICE

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE

DOOR FOR RAILWAY HOPPER CARS

Application filed October 5, 1929. Serial No. 397,592.

My invention relates to the construction of railway cars of the dumping or drop bottom type, such as hopper cars, hopper gondola cars, drop bottom or general service 5 gondola cars or the like, having a door forming a part of the load retaining means, which door is provided with hinges adjacent one of its edges and is capable of being dropped or swung open to discharge the load. Any 10 means of raising the door to the closed position and any means for locking and releasing the door may be employed with my door.

Though the door may be made of a rolled steel plate pressed to form between reciprocating dies, I prefer to make the door of cast metal because a better distribution of the metal for strength requirements can be obtained without the use of separate fixtures, and furthermore, cast metal has greater 20 resistance to corrosion than rolled steel.

An object of the invention is to provide a door of cast metal formed and shaped so that it will not be deformed by warping when cooling, and furthermore, will eliminate shrinkage cracks and internal stresses.

Another object of the invention is to reinforce a hopper car door in such a way to also increase the cubical capacity of the car.

Another object of the invention is to form 30 the marginal portions of the door so as to obtain the maximum strength to resist deflection of the door.

In the drawings:

Fig. 1 shows a plan view of a typical door 35 incorporating my improvement.

Fig. 2 is a section on line 2—2 of Fig. 1.

Fig. 3 is a section on line 3—3 of Fig. 1.

Fig. 4 is a side view of Fig. 1.

Fig. 5 is a diagram described later.

40 The door comprises marginal portions 2 and a depressed portion 3 connected by a preferably continuous web 4. This marginal portion is inclined downwardly toward the outer edges of the door.

45 When a load is imposed upon the central

or depressed portion 3 of the door the stresses are transmitted through the web 4 to the marginal portion or flange 2 causing a tendency for the flange to deflect, and the object of this invention is to so position this flange 50 relative to the web so as to obtain the least tendency toward deflection, thereby obtaining the maximum strength of the web and flange.

The proper angular relation between the 55 flange and the web is obtained, as shown in the diagram, Fig. 5. Line $a-a$ is drawn at right angles to the web and line $a-b$ bisects the angle C between line $a-a$ and line $a-d$ parallel to the depressed portion 3. The line 60 $e-e$ (parallel to the marginal portion) is parallel to line $a-b$; in other words, the marginal portion 2 is substantially parallel to a plane bisecting the angle between the plane of the depressed portion 3 and a plane 65 normal to the web 4.

This device is an improvement upon the construction shown in my application Serial No. 392,632, filed September 14, 1929.

The accompanying drawings illustrate the 70 preferred form of the invention, though it is to be understood that the invention is not limited to the exact details of construction shown and described, as it is obvious that various modifications thereof, within the 75 scope of the claims, will occur to persons skilled in the art.

I claim:

1. A hingeable door forming part of the load retaining means of a railway dump car 80 comprising a marginal portion, a depressed portion in a spaced apart plane therefrom, and a web connecting said portions, said marginal portion being inclined downwardly toward the outer edges of the door.

85 2. A hingeable door forming part of the load retaining means of a railway dump car comprising a marginal portion, a depressed portion in a spaced apart plane therefrom, and an oblique web connecting said portions, 90

said marginal portion being inclined downwardly toward the outer edges of the door.

3. A hingeable door forming part of the load retaining means of a railway dump car comprising a marginal portion, a depressed portion in a spaced apart plane therefrom, and an oblique web connecting said portions, said marginal portion being inclined downwardly toward the outer edges of the door, said marginal portion being substantially parallel to a plane obtained by bisecting the angle between the plane of the depressed portion and a plane normal to the web.

GARTH G. GILPIN.
